UNITED STATES PATENT OFFICE.

WEBSTER C. ESTES, OF BROOKLYN, NEW YORK.

DESIGN FOR A BOX.

SPECIFICATION forming part of Design No. 16,578, dated March 23, 1886.

Application filed January 29, 1886. Serial No. 190,129. Term of patent 7 years.

To all whom it may concern:

Be it known that I, WEBSTER C. ESTES, a citizen of the United States, residing at Brooklyn, Kings county, New York, have invented and produced a new and original Design for Boxes, of which the following is a specification, reference being had to the accompanying drawings, forming part thereof.

Figure 1 is a perspective view of my newly-designed box. Fig. 2 is a plan view of the same, and Fig. 3 is a longitudinal sectional view taken in the plane indicated by the line 3 3 in Fig. 2, these three views being deemed necessary to fully illustrate my design.

The class of boxes to which I apply my new design comprises such as are of cylindrical form, and each having a body and a removable cover.

A represents the body of the box, and B its cover. When viewed in plan, the contours of both body and cover are circular.

The novel feature of this design lies in the contour of the cover B. The lower section, a, of the cover is circular in plan, and its plan contour-line coincides substantially with that of the body A. At b there is an offset where the side contour-line of section a of the cover

joins that of the section c. The section c is circular in plan, its plan contour-line being concentric with the plan contour-line of section a and falling within the latter. On the section c is a bead-like or ring-like projecting ornament, d, as clearly shown in the accompanying drawings.

This design imparts to the box an appearance somewhat similar to that of a bottle provided with a stopper or cork.

I claim—

The design for a box herein described, the same consisting of the box-cover B, having the cylindrical lower section, a, the cylindrical upper section, c, of less diameter than the section a, the offset at b, and the square bead-like projecting ornament d, on the section c, substantially as shown in the accompanying drawings.

In witness whereof I have hereunto signed my name in the presence of two subscribing witnesses.

WEBSTER C. ESTES.
